UNITED STATES PATENT OFFICE

139,872

DESIGN FOR A GAME BOARD

Charles Jerome Shimer, Pen Argyl, Pa.

Application October 17, 1944, Serial No. 115,827

Term of patent 14 years

(Cl. D34—5)

To all whom it may concern:

Be it known that I, Charles Jerome Shimer, a citizen of the United States, residing at Pen Argyl, in the county of Northampton and State of Pennsylvania, have invented a new, original, and ornamental Design for a Game Board, of which the following is a specification, reference being had to the accompanying drawing, forming part thereof.

I claim:

The ornamental design for a game board, as shown.

CHARLES JEROME SHIMER.
